UNITED STATES PATENT OFFICE.

ARTHUR L. KIFF, OF CORNING, NEW YORK.

ACETYLENE-GAS GENERATOR.

SPECIFICATION forming part of Letters Patent No. 657,549, dated September 11, 1900.

Application filed January 18, 1899. Serial No. 702,539. (No model.)

To all whom it may concern:

Be it known that I, ARTHUR L. KIFF, a citizen of the United States, residing in Corning, in the county of Steuben and State of New York, have invented certain new and useful Improvements in Acetylene-Gas Generators; and I do hereby declare the following to be a full, clear, and exact description of the invention, such as will enable others skilled in the art to which it appertains to make and use the same.

The invention has reference more particularly to apparatus for generating gas by the admixture or combination of a solid with a liquid, as calcium carbide with water, for the production of acetylene gas for illuminating and other purposes.

One object of the invention is to provide means for controlling the feed of the calcium carbide to the water in the generator by the lessening force or expansive power of the gas in the holder due to its consumption.

Further objects are to increase the capacity and effectiveness of the apparatus and provide simplified devices for feeding the carbide to the water in the generator in predetermined or measured quantities.

The above and additional objects are attained by the means illustrated in the accompanying drawings, in which—

Figure 1 is a vertical sectional view of an acetylene-gas generator constructed and arranged in accordance with my improvements. Fig. 2 is a horizontal sectional view showing more clearly the means for effecting the release of the trays which hold the measured quantities of calcium carbide. Fig. 3 is a similar view to Fig. 1, but showing a modification in the arrangement of the tilting trays and the means for operating the catches to effect this release. Fig. 4 is a similar view to Fig. 2, showing more clearly the arrangement indicated in Fig. 3. Fig. 5 is a detail of the means for effecting in a progressive manner the operation of the devices which successively release the trays.

Preliminarily to a more detailed description it may be stated that my improved gas-generating apparatus comprises a number of hinged or pivoted trays upon which measured or predetermined quantities of the carbide are placed, and these trays are arranged or su-

perposed one above another in a case or cabinet which is in open communication with the generator, which contains the water into which the carbide is dumped or precipitated. The spaces between the trays constitute compartments of any desired capacity, and said trays are supported or held in horizontal positions by means of suitable catches, which are operated successively to release the trays, so as to enable them to fall or drop to a vertical position, and thereby deliver the carbide to the water below. The case or cabinet in which the trays are contained is preferably arranged in an inclosing shell or casing from which the cabinet is removable, so as to enable a new set of trays to be inserted in position after one set has been dumped and relieved of its contents. A cover is provided for the outer inclosing case for enabling the insertion and removal of the trays to be quickly effected. The means for operating the catches for successively releasing the trays comprises suitable devices carried by a shaft which is operated by the descending movement of the movable case of a telescopic gasometer or holder, into which the gas passes from the generator.

Reference being had to the drawings, 1 denotes an ordinary tank or generator containing water 2, said tank being open at the top, as shown at 3, and provided with an annular flange 4, so as to support an upper shell or casing 5, which is provided with a flange 6, fitting or seated upon said flange 5, to which it may be secured by any suitable means. In Fig. 1 the said flange 6 is extended on one side, so as to form the bottom 7 of a chamber 9, which incloses the operating-shaft 8 of the releasing devices hereinafter referred to. The chamber 8 is included within the shell or casing 5, and when reference is hereinafter made to the latter it will be understood that both are meant.

Located in the casing 5, so as to be in open communication with the generator 1, is an inner case or cabinet 10, of any suitable shape or configuration in cross-section, but preferably corresponding with that of the shell 5. This cabinet rests at its lower end upon an inner flange 11 at the lower end of the casing 5 and is removable through the opening 12 at the top of said casing. The opening 12 is

closed by a lid or cover 13, which is held in place tightly by means of screws 14 14, passing through a bridge-piece or yoke 15 and operated by hand-wheels 16. The bridge-piece is removably secured in place by means of bolts 17.

Arranged within the inner case or cabinet 10 is a series of shelves or trays 18, one above another, and each tray is hinged or pivoted 10 at 19 to one side of the cabinet, so as to be capable of falling or dropping to a vertical position by its own weight or gravity. It is upon these trays that the calcium carbide 20 is placed in proper measured quantities, and 15 the trays are supported in horizontal positions by suitable means adapted to be tripped to release them. As herein shown, Fig. 2, said means consists of catches 21, which are pivoted at 22 upon short ledges 23, projecting from one side of cabinet 10, said catches normally projecting into the cabinet and serving to support the trays in the manner shown. As thus constructed and arranged it is essentially necessary that the trays be 25 tilted or dumped one after another in succession, beginning with the lowermost, and while different means could be employed for this purpose I prefer the devices which I will now describe.

30 The operating-shaft 8 hereinbefore mentioned is provided with a series of arms or fingers 25, which are equal in number to the number of trays in the series and which are disposed radially about the shaft in such position as to successively engage the catches for the trays, and thereby release the latter in regular order. For instance, on a partial rotation of said shaft the lowermost finger 25 will operate to release the lowermost tray, 35 and when the shaft is next given a continued partial rotation the next lowermost finger will be brought into engagement with the catch of the next lowermost tray, and so on until all the trays of the series are operated. 40 On the dropping or tilting of each tray the carbide thereon is precipitated into the water in the generator and a quantity of acetylene gas is immediately evolved from the admixture of the two substances, the gas passing 45 from the generator to the space 26 in the movable case 27 of the gasometer 29, through the pipe 28, leading from the former to the latter. As the gas is conducted from the space 26 by means of pipe 29 for consumption the said 50 movable case is lowered automatically on account of the decreasing force or expansive power of the gas therein, and it is this movement of said movable case that is utilized for effecting the intermittent operation of the 55 shaft 8. For this purpose the said shaft is provided at its lower end with a beveled gear-wheel 30, which meshes with a similar gear-wheel 31, carried at the inner end of a horizontal shaft 32, that is supported in hangers 60 and 34 from the inclosing casing 5. At its outer end the shaft 32 carries a ratchet-wheel 39, the teeth of which are engaged by the end

of a pawl 40, carried by an arm 41, attached to the side of the movable case 27. It will be seen that when the first tray is dropped a certain amount of gas will be generated and the case 27 will be caused to rise. As soon as the gas-pressure is relieved the case descends, whereupon the shaft 32 is partially rotated by the engagement of pawl 40 with ratchet-wheel 39, and consequently the shaft 8 is partially rotated to bring the next finger thereon into position for operating the tray corresponding thereto in position. After all the trays have been operated the whole series 80 can be readily removed by taking out the case or cabinet and a new one containing another series inserted.

In Figs. 3 and 4 I have shown a modification of my invention wherein I employ a number or multiple series of trays, which are disposed concentrically about the operating-shaft 8 in separate "flats" or horizontal rows, each vertical series in this instance comprising ten trays and each flat or horizontal 90 row being also composed of ten trays. With such an arrangement it is desirable that the trays of each flat be first operated one after another or in succession and that the several series also be operated successively in the order 95 represented in Fig. 1. To effect this, I provide the operating-shaft 8 with a number (ten) of separate sleeves 50, each of which, with the exception of the lowermost one, is loosely sleeved on said shaft, while said lowermost 100 sleeve is fixed on and turns with the shaft. Each sleeve is provided with an arm or finger 51, corresponding with the catches of one of the tray-flats, and said fingers are so disposed about the shaft that by the time the shaft 105 has made a complete revolution and effected the release of all the trays of one flat the next finger is brought into action for operating the trays of the next flat, and so on. The catches and operating-fingers, therefore, are the same 110 in this construction as those already described with reference to Figs. 1 and 2. The lowermost sleeve 50 is provided at its upper end with a lug or projection 60, which engages with a similar lug or projection 61 on the lower end 115 of the sleeve next above, and this second sleeve is also provided on its upper end with a similar lug or projection 60, which engages with a similar projection 61 on the third sleeve, and so on throughout the whole number of 120 sleeves. The action of this arrangement is as follows: At the commencement of operations the lowermost trays or those comprising the lowermost flat will be successively released by the finger 25 of the lowest sleeve 50, and as 125 the shaft turns the projection 60 on the other end of said sleeve engages the projection 61 on the sleeve next above, when that sleeve thereby becomes locked to the shaft and is operated in a similar manner, and so on 130 throughout the whole number of sleeves. By referring to Fig. 5 the construction of the sleeves 50 will be fully understood. In the operation of the device the shaft 8 rotates

- freely within all the sleeves 50, which are loose upon it, as above described. Immediately on the starting of the shaft the finger 25 on the fixed sleeve begins to dump the trays 5 in the lowermost flat, all the other sleeves remaining stationary (or if moved at all the movements not being sufficient to trip the catches) until the shaft has made one revolution, when the second sleeve is locked to 10 the shaft by its engagement with the first-mentioned. Another revolution of the shaft then takes place and the third sleeve is locked to the first and second, all above the third being meanwhile stationary. This locking of 15 the sleeves to the shaft goes on until they are all positively engaged with one another, and every time a new sleeve is locked to the one beneath it a new flat of trays begins to be dumped.
- 20 With the construction shown in Fig. 3 a single removable cover may be employed for the apparatus, or there may be a separate cover for each vertical series of trays. Also in said figure a single cabinet only may be 25 employed for all the trays, or a separate one may be used for each series of trays, as shown.
- Without limiting myself to the precise details of construction and arrangement shown and described, I claim—
- 30 1. In an acetylene-generator, the combination with a water-tank, of a series of stationary tilting carbid-trays, said trays being superposed one above another over the tank, catches for supporting the trays in horizontal 35 position, and a vertical rotary shaft provided with means to engage the catches and release the trays in regular order beginning with the lowermost.
2. In an acetylene-generator, the combination 40 with a water-tank, of a series of stationary tilting carbid-trays, said trays being arranged in flats superposed one above another over the tank, catches for supporting the trays in horizontal position, and a vertical rotary shaft provided with means to engage the catches and release the trays in regular order beginning with the lowermost and the trays of each flat being released before those of the flat next above.
- 45 3. In an acetylene-generator, the combination with a water-tank, of a superposed casing, a series of stationary removable tilting carbid-trays inclosed in said casing, said trays being arranged vertically one above another, 55 catches for holding said trays in horizontal position, and a vertical rotary shaft provided with means to engage and release the catches of said trays in regular order beginning with the lowermost.
- 60 4. In an acetylene-generator, the combination with a water-tank, of a superposed casing, a stationary removable cabinet inclosed in said casing, a series of stationary tilting carbid-trays arranged in said removable cabinet one above another, catches carried by 65 said cabinet for holding the trays in horizontal position, and means to engage and release

the catches of said trays in regular order beginning with the lowermost.

5. In an acetylene-generator, the combination 70 with a water-tank, of a superposed casing, a stationary annular cabinet removably inclosed in said casing, a series of stationary tilting carbid-trays arranged in flats in said removable annular cabinet, one above another, catches carried by said cabinet for holding the trays in horizontal position, and a vertical rotary shaft arranged centrally of the annular cabinet and provided with means to engage and release the catches of the trays 80 in regular order beginning with those of the lowermost flat.

6. In an acetylene-generator, the combination 85 with a water-tank, of a series of superposed tilting trays arranged in flats, each tray being adapted to hold a quantity of carbid, a rotary operating-shaft, a series of superposed sleeves on said shaft, the lowermost one of which is fixed on the shaft, and the remainder being capable of turning thereon, engaging 90 devices between the sleeves, and means on the sleeves for successively operating the trays to dump their contents into the water in the generator.

7. In an acetylene-generator, the combination 95 with a water-tank, of a series of radially-arranged superposed tilting trays for holding quantities of carbid, means for supporting the trays in horizontal positions, a central rotary shaft, a series of normally-loose sleeves 100 on the shaft provided with fingers for successively tilting the trays, a fixed sleeve at the lower end of the shaft, and engaging devices between the sleeves whereby the normally-loose sleeves are successively locked to 105 the shaft as the latter revolves.

8. In an acetylene-generator, the combination 110 with a water-tank, of an outer casing, a removable cabinet in said casing, a series of superposed tilting trays arranged in said cabinet for holding carbid, catches for supporting the trays in horizontal positions, a rotary shaft having fingers to release the catches, a telescopic gas-holder, pipe connections between 115 the latter and the generator, and means intermediate said holder and the tray-operating shaft whereby said trays are released successively to dump their contents into the water.

9. In an acetylene-generator, the combination 120 with the generator, of a casing supported by the same having a removable cover, a removable cabinet supported in said casing and communicating at its lower end with the generator, a series of superposed hinged trays forming compartments in the cabinet, catches 125 for supporting said trays in horizontal positions, a rotary shaft having fingers located in position to engage and release said catches, a telescopic gas-holder, pipe connections between the latter and the generator, a pawl 130 carried by the said gas-holder, and an intermediate shaft geared to the finger-carrying shaft, and having a ratchet-wheel operated by the descending movements of the holder.

10. In an acetylene-generator, the combination with a water-tank, of an annular series of stationary trays for holding carbid, the trays of each series being arranged one above the other, a rotary vertical shaft adjacent said trays, catches for holding said trays, and means on the shaft to successively engage the catches to dump the trays.
11. In an acetylene-generator, the combination with a water-tank, of a casing superposed above the tank, a series of tilting shelves or trays each adapted to hold a measured quantity of carbid, and to discharge the same by gravity through the casing into the tank below, catches for holding the shelves or trays in horizontal position, and means for automatically releasing the catches so as to dump the shelves or trays in regular order beginning with the lowermost.
12. In an acetylene-generator, the combination with a water-tank, of a casing superposed above the tank, a series of tilting shelves or trays forming partitions which when in horizontal position divide the casing into receptacles adapted to hold measured quantities of carbid, and arranged to discharge the same by gravity through the casing into the tank below, catches for holding said shelves or trays in horizontal position, and means for releasing the catches so as to dump the contents of the carbid-receptacles into the water in regular order beginning with the lowermost.

nation with a water-tank, of a casing superposed above the tank, a series of tilting shelves or trays forming partitions which when in horizontal position divide the casing into receptacles adapted to hold measured quantities of carbid, and arranged to discharge the same by gravity through the casing into the tank below, catches for holding said shelves or trays in horizontal position, and means for releasing the catches so as to dump the contents of the carbid-receptacles into the water in regular order beginning with the lowermost.

In testimony whereof I affix my signature in presence of two witnesses.

ARTHUR L. KIFF.
